HAT

Ernest Parlow, New York, N. Y.

Application April 28, 1934, Serial No. 722,827

6 Claims. (Cl. 2—192)

The invention relates to a hat of which the entire hat, or at least the major portion of the hat, is formed of one integral piece of material, and the invention also relates to the method of 5 making such hat.

The primary object of the invention is to provide a form of hat of either a brim or visor type, or even a hat consisting solely of a crown, which 10 hat can be used conventionally, and which can be manufactured so cheaply as to permit its use incidentally as a hat but more particularly as an 15 advertising device which can be given away.

The invention features a hat which can be formed from a flat piece of semi-rigid material, 20 such as cardboard, capable of being slotted in a simple die cutting operation to form a complete marketable article which the user can easily distort into a hat shape, and where the device is designed to function as an advertising article, the 25 providing of a flat surface to the original blank which can be readily printed or stamped or otherwise decorated with advertising material.

Various other objects and advantages of the 30 invention will be in part obvious from an inspection of the accompanying drawing and in part will be more fully set forth in the following particular description of one form of hat embodying the invention, and the invention also consists in certain new and novel features of construction 35 and combination of parts hereinafter set forth and claimed.

In the drawing:

Fig. 1 is a plan view illustrating a preferred 40 embodiment of the invention and illustrating the slotted blank forming the first or factory step in the method of forming the completed hat; and

Fig. 2 is a view in side elevation of the completed hat formed by the user from the slotted blank shown in Fig. 1 and illustrating a beach 45 hat having a perforated crown.

In the drawing there is shown part of a circular blank 10, in the instant case being a sheet of semi-rigid cardboard of a stiffness to cause the brim of the beach hat herein illustrated to 50 maintain its configuration. In actual practice a graceful form of drooping brim has been obtained by making the blank of less rigid material and securing a chin or head strap conventionally to the brim at diametrically opposite sides adjacent 55 its inner perimeter. While the hat may, of course, be constructed of a material which will last for some period of time, the device illustrated is designed to be sold so cheaply as to warrant its being thrown away at the end of a day's use. It

is further suggested that the cardboard blanks be covered with cloth 11, paper, or otherwise decorated to produce any desired pleasing, artistic, or grotesque effect.

The blank is formed circular, elliptical, or of other desired shape in outline, and is then subjected to a slitting operation by the use of properly designed and positioned cutting dies to provide an annular group of series of slits 12 which extend through the blank. The slits forming 10 each series as shown in Fig. 1 are arranged in the form of concentric circles, that is, in end to end relation in circular or endless curved form but the slits may be arranged in other forms of conic sections or in other shapes of endless lines where 15 the desired form of the crown is to be elliptical, egg, or head-shaped. The slits are relatively short compared to the length of the interrupted circle formed thereby, and are of progressively greater length from the innermost circle or series 20 13, to the outermost circle or series 14, and in the illustrated form there are eight equidistantly and circumferentially spaced slits to each circle with each slit being substantially the same length as the other slits in its particular series or circle. 25 The slits of one circle are so arranged relative to the slits of the next adjacent two circles that they are in radially offset relation. Differently expressed each end, say the opposite ends 15 and 16 of each slit, is intruded between the adjacent 30 ends 17 and 18 of the contiguous slits of the next adjacent inner and outer circle of slits. This arrangement of slotted portions forms in addition to the slotted portion an outer brim 19 and a flat unslotted circular top central portion 35 20 to the crown 21 of the completed hat.

To form the hat from the blank so slotted, the central portion 20 is pushed upwardly, that is, is displaced transversely from the plane of the blank and from the plane of the brim forming 40 portion 19. This expands or opens up the slotted material to form a lattice effect or honey-comb form of open work material forming the side 22 of the frusto-conical crown. There is formed in the distended crown a plurality of hexagonal up-standing openings 23 with adjacent openings separated by long flat rectangular strips 24. As the strips 24 are for the most part horizontal or almost so, their accumulated effect is that they provide an extensive shade area to the crown 45 and are particularly effective in shading the head from vertically directed sun rays. In other words the openings 23 extend vertically adjacent the brim and become inclined to the vertical as they approach the top of the crown but the flat strips 50 55

which form the openings extend horizontally and are progressively offset so that viewed in plan in either the collapsed or distended positions of the crown portion the hat as a whole has a shading area equal to the entire area of the original blank.

The hat can be used as an open-work hat and the wearer's hair showing through the openings gives a pleasing effect. Even when made of cardboard the crown will hold or at least substantially hold its form, but it is obviously within the scope of the disclosure to provide a hat lining for the crown portion if desired.

After it is worn the hat can be recollapsed back into its original flat form thus permitting ready stacking of one hat upon another and permitting an easy carrying of each hat.

It is understood that all available space, such as both sides of both the brim 10 and the central portion 20 provide blank space available for printing, or the showing of other advertising matter and this matter may, of course, even extend across the slitted portion.

The securing of a strap to the cardboard brim is apt to tear the same. Accordingly it is herein suggested that a pair of attaching clamps or buttons 25 be located on diametrically opposite sides of the crown. These buttons are shown to include an apertured projection 26 which extends through the cardboard and has the ends of a fastening strap 27 secured thereto.

While there has been shown, described and pointed out in the annexed claims, certain novel features of the invention, it will be understood that various omissions, substitutions and changes in the form and details of the hat illustrated and in its use may be made by those skilled in the art without departing from the spirit of the invention.

40 I claim:

1. A one-piece hat formed of a single layer of material and including an outlining brim and a crown, said crown having a flat top portion ex-

tending parallel to the brim, the side of the crown between the top portion and brim being of frustoconical outline forming a lattice work effect and providing a plurality of hexagonal openings extending parallel to the plane of the brim and top portion and each opening being separated from a next adjacent opening by a long flat strip of material.

2. A one-piece hat including a brim and a crown, said crown being of substantially frustoconical outline with its side forming a lattice effect and providing a plurality of openings extending parallel to the plane of the brim and each opening being separated from a next adjacent opening by a long flat strip of material.

3. A hat provided with a slitted portion, with the slits forming said portion arranged in concentric lines and in radially staggered relation, with each end of each slit projecting between the ends of the two adjacent slits in the two next adjacent concentric lines.

4. A flat blank for forming a hat, provided with a series of slits, with the slits of each series spaced apart in an endless curved line and the slits of each series offset from the slits of the next adjacent series.

5. A hat including a flat brim, a crown with the sides thereof forming an open lattice-work, certain parts of said lattice-work comprising narrow strips of material extending parallel to the plane of the brim and adapted to engage the head of the wearer edgewise.

6. A flat blank for forming a hat, provided with a group of series of slits including an outer series and an inner series within the outer series, the slits of each of said series being each of substantially the same length and spaced apart in end to end relation in an endless curved line, and the slits of the inner series being confined within the area outlined by the endless line of slits forming the outer series.

ERNEST PARLOW.
